HANDLE GRIP

Robert E. Utz, Dayton, and Read Viemeister, Yellow Springs, Ohio, assignors to The Huffman Manufacturing Company, Dayton, Ohio, a corporation of Ohio

Filed Mar. 29, 1963, Ser. No. 74,213

Term of patent 14 years

(Cl. D90—11)

FIG-1

FIG. 1 is a perspective view of a handle grip showing our new design;

FIG. 2 is a side elevation view of our design;

FIG. 3 is a top plan view thereof;

FIG. 4 is a bottom plan view thereof;

FIG. 5 is an end view of our design as viewed from the left end of FIG. 2; and

FIG. 6 is another end view of our design as viewed from the right end of FIG. 2.

The dotted line showing of a fragmentary typical handle bar is for illustrative purposes only.

We claim:

The ornamental design for a handle grip, substantially as shown and described.
